UNITED STATES PATENT OFFICE.

ALEXANDER MCKAY, OF MONTREAL, QUEBEC, CANADA.

CENTRIFUGAL DRIER.

Application filed October 18, 1924. Serial No. 744,476.

To all whom it may concern:

Be it known that I, ALEXANDER MCKAY, a subject of the King of Great Britain, and resident of the city of Montreal, in the Province of Quebec and Dominion of Canada, have invented certain new and useful Improvements in Centrifugal Driers, of which the following is a full, clear, and exact description.

10 This invention relates to new and useful improvements in driers and more particularly to centrifugal driers, and the object of the invention is to provide a device which will quickly, thoroughly and inexpensively dry material such as sand, stone, ore, and other comminuted bodies.

15 Another object is to provide a drier of simple and durable construction, which will distribute the material to be dried into a thin uniform layer from which the moisture will escape readily.

20 A further object is to provide a drier which by its construction will regulate the flow of material to be dried according to the moisture held by the material in its passage through the machine.

25 In my invention, I provide a drying column of cylindrical formation, which may consist of a plurality of flanged units bolted or otherwise secured to one another by their flanges. The top of the column is provided with a cover having an inlet for the material to be dried and an outlet for the spent heating or drying agent, which may be supplied to the bottom of the column from a source (not shown). The lower part of the column is provided with an inverted conical bottom or hopper, having an outlet formed therein to facilitate the removal of the dried material. Securely attached to a shaft rotatably mounted in bearings formed in or secured to the cover and bottom of the column are a plurality of discs, adapted to spread the material uniformly in the form of a thin layer, so that the maximum amount of surface of the material will be subjected to the maximum amount of heat during the progress of the material through the machine. The discs are graded to regulate and assist the flow of the material through the machine. Baffles or hoppers are also provided within the column to assist the drying operation of the material.

30 In the drawing, I have shown an eleva-

tion partly in section of one embodiment of my invention.

35 In this drawing, 11 designates a plurality of column units preferably cylindrical and all exactly alike. The units may be provided with flanges 12 through which bolts 60 may be placed to hold the units together, so that as many units as desired may be assembled to form a drier column of any desired height. At the top of the drier, there is provided a cover 13 carrying a bearing 14 disposed substantially concentrically with the shell. The cover also carries a charging spout or chute 15 directed toward the axis of the device and an outlet stack 16 for the spent heating agent and dust. At the lower 40 end of the drier there is provided an inverted conical bottom 17, from the apex or lower point of which extends a discharging chute or conduit 18 for dried material. A heating agent, such as hot air, may be admitted anywhere at the lower end of the device but preferably through a conduit 19 connecting with the upper part of the conduit 18. The object of this arrangement is to keep the mouth of the conduit 19 free 45 from obstruction by material passing through the drier. The bottom also carries a bearing 20 disposed concentrically of the shell. A series of inverted frusto-conical chutes or hoppers 21 are provided, one above 50 the other within the shell. The chutes may conveniently be secured by engagement of their outer and upper edges between the flanges of adjacent column units. These 55 chutes are preferably made of thin material, which will quickly absorb heat from the drying agent. They also form heat retaining pockets 21^a to retard the progress of the heating agent through the drier, so that as much heat as possible may be absorbed by 60 the various portions of the drier from the heating agent. A plurality of shaft sections 22 are provided, axially coincident with the column and conveniently provided with flanges 23 for bolting them together. The drier plates or pans 24, 25, 26 and 27 65 may be conveniently attached to the shaft by bolting them between the adjacent shaft sections. Obviously, the construction of the shaft and the method of attaching the drier plates thereto may be varied as desired. The shaft is journaled in the bearings 14 and 20 70 to maintain it and the plates concentric with 75 the shaft. The shaft sections 22 are provided with flanges 28 for bolting them together. The 80 flanges 28 are provided with holes 29 for receiving the bolts 30. The flanges 28 are provided with 85 slots 31 for receiving the bolts 30. The flanges 28 are provided with 90 slots 31 for receiving the bolts 30. The flanges 28 are provided with 95 slots 31 for receiving the bolts 30. The flanges 28 are provided with 100 slots 31 for receiving the bolts 30. The flanges 28 are provided with 105 slots 31 for receiving the bolts 30.

the shell, and may be supported and driven by any suitable means (not shown). The arrangement is preferably such that there is a drying plate over each hopper 21, considering the drier from the top downwards. At the bottom of the drier, the conical end 17 corresponds with and replaces the ordinary hopper. As will be clearly seen, the drier plates or discs are of smaller diameter than the shell or column, while the hopper or chutes 21 are of the same external diameter and have central openings. The drier plates 24, 25, 26 and 27 have their upper surfaces curved or dished in a manner to provide elevated central and peripheral portions. Comparing the plates, it will be noted that the elevation of the central portion 28 of the plate 24 is slightly greater than the elevation of the central portion 29 of the plate 25. It will also be noted that the elevation of the central portion 29 of the plate 25 is greater than the elevation of the central portion 30 of the plate 26, and that the elevation of the portion 30 is greater than the elevation of the centre portion 31 of the plate 27. It will be seen that the plates are of different curvatures through the variation in the heights of their respective centre portions, the plate at the top of the column 30 having the highest central portion, while the plate at the bottom has the lowest central portion, the intermediate plates being provided with central portions varying in height between the highest and the lowest. In the drawing, I have shown only four plates, but this is for illustrative purposes only, and the number of plates and corresponding hoppers may be increased or decreased according to requirements. It will be noticed that these drier plates are made of thin material and provide a recessed portion under their centres. The recessed portions act as baffles and retard the progress of the heating agent through the machine, so that the maximum amount of heat may be utilized for drying the material as it passes through the machine. The edges 33 of the plates are turned upwardly to form a rim to spread and throw the material against the side walls of the cylindrical column in a uniform manner.

The operation of the device is as follows:

Warm air is fed into the device through the conduit 19, and is retarded in its progress through the drying chamber by the hoppers and drier plates. The air comes in contact with the underside of the plates, and is guided into the pockets 21 by the curvature of the rim, which prevents a direct flow of the heating agent through the apertures formed in the hoppers. This construction allows the hoppers and drier plates to absorb heat from the heated air, in order to increase the efficiency of the ma-

chine. The shaft is rotated from a source (not shown). The material to be dried is fed into the drying chamber through the chute 15, in such a manner that it falls at the centre of the uppermost drier plate. The material slides down into the grooved or dished portion of the plate against the sides of the drier frame or column by means of the curved rim. The material in its passage to the frame describes an arc and then falls on to the hopper immediately below the drier plate, said hopper being so positioned that it guides the material toward the centre of the drier plate immediately below the hopper, from where it is again thrown against the walls of the drier. This cycle of operation is repeated until the material leaves the lowermost disc, from where it falls into the discharge hopper 17 and through the pipe 18 to a storage bin (not shown). The material is thrown off the plates by centrifugal action. The uppermost plate is provided with a high central portion to assist the initially damp material in its outward passage from the plate, so that parts of the material thrown from the edge of the plate will tend to separate and spread evenly from the edge of the plate. The material is also assisted in its separation by coming in contact with the inner walls of the drier from where it is led on to the second drier plate by means of the hopper. The plates taken in order from top to bottom of the drier are gradually reduced in height with regard to their centre portions, as the material is gradually broken up and the lower discs are used more for spreading the material in a thin uniform layer than the ones immediately above them. This distribution of the material is essential to allow the heat to come in contact with the grains of the material to thoroughly dry same. The gradual alteration of the heights of the centre portions of the discs, also tends to regulate and assist the flow of material through the drier, which is so constructed that the maximum amount of heat is utilized for drying purposes, thereby increasing the efficiency of the machine. The drier column is provided with an outlet stack for dust and for the spent heating agent.

The device forms a simply operated device which quickly and economically dries materials, such as sand, stone, ore and other comminuted bodies.

Having thus described my invention, what I claim is:

1. In a centrifugal drier, a drier column, a plurality of curved drier plates rotatably mounted in the centre of the column, such plates being mounted one above the other and differing in their respective curvatures, the difference being made in the respective heights of the centre portion, the plate with

the highest centre portion being placed at the top of the column and the plate with the lowest centre portion being placed at the bottom of the column, with the heights of 5 the centre portions of the plates between varying between the heights of the centre portions of the uppermost and lowermost plates, a plurality of inverted frusto-conical hoppers placed between each drier plate 10 and mounted in the column and secured thereto, the plates and the hoppers being made of thin material and adapted to form pockets on their lower sides to provide baffles for a drying agent fed into the bottom of 15 the column, said hoppers having their lower ends open and so positioned with reference to the drier plates as to deliver material on to approximately the highest central portions of said plates, means positioned at the 20 top of the column for feeding the material to be dried on to the centre of the uppermost drier plate, means positioned at the bottom of the column for withdrawing the dried material, and means for withdrawing dust 25 and the spent heating agent from the column.

2. A device according to claim 1, having the edges of the plates of different curva-

ture turned slightly upwardly and adapted to overlie the central parts of the conical 30 hoppers directly below them.

3. In a centrifugal drier, a drier column, inverted conical hoppers mounted in said column, a plurality of dished drier plates rotatably mounted in the drier column, each 35 plate being dished to provide elevated central and peripheral portions, the central and peripheral portions of the several plates being made of varying height, the plate with the highest central portion and shallowest 40 peripheral portion being placed at the top of the column and the plate with the lowest central portion and the highest peripheral portion being placed at the bottom of the column, the arrangement being such that 45 each plate is formed with a central portion of less height than the corresponding portion of the plate next above and with a peripheral portion of greater height than the peripheral portion of the plate next 50 above, and means for rotating said plates including a supporting shaft connected therewith.

In witness whereof, I have hereunto set my hand.

ALEXANDER MCKAY.
